UNITED STATES PATENT OFFICE

2,131,287

DOUBLE BOILER

Walter T. Kelley, Paducah, Ky.

Application January 4, 1938, Serial No. 183,387

1 Claim. (Cl. 53—1)

This invention relates to heaters or boilers for heating or processing honey or other liquids, semi-solids or solids, and the general object of the invention is to provide a heater or boiler 5 of this character so constructed that heat is applied only at the bottom of the container or boiler where the coldest part of any liquid or semi-liquid remains during the heating process, so that the warmed up parts of the liquid rise 10 and are not reheated and caused to deteriorate as in other styles of double boilers known to me.

A further object is to provide a device of this character which, as before stated, is particularly adapted for processing honey and which is so 15 constructed that the honey will not be burned or overheated and which shall be particularly simple and cheap to construct.

My invention is illustrated in the accompanying drawing wherein:

Fig. 1 is a top plan view of the structure shown 20 in Fig. 2.

Fig. 2 is a vertical section of the structure shown in Fig. 1.

Referring to the drawing, 10 designates the 25 body of the boiler, this body constituting a container. The body 10 has a lower bottom 11 and an upper bottom 12, defining between these double bottoms the space 13. The bottom 12 is preferably slightly conical, that is, it rises up toward 30 the center of the container 10 and at this point is connected to a vent pipe 14 which extends upward from the center of the bottom 12 to the full height of the container 10 and at its upper end is supported by means of a transversely extending brace 15. Extending from one side of 35 the boiler 10 just above the lowest portion of the bottom 12 is a faucet or discharge spout 16 provided with a valve or gate 17. For the purpose of filling the water space 13, I provide the inlet 40 hopper 18 which extends upward on the side of the container 10 and has an open top and at its lower end opens into the interior of the space 13. A drainage opening 19 may be provided in the lower end of this inlet hopper or any other 45 point in the bottom 11, the purpose being, of course, to drain out the water from the space 13 when desired. The hopper 18 extends up high enough above the upper portion of the space 13

as to indicate when this space 13 has been filled with water. Thus the member 18 constitutes means whereby the level of water may be observed.

Obviously the container 10 or boiler proper 5 is to be filled with liquid such as honey, while the space 13 is to be filled with water. The boiler is then placed upon a stove or over any source of heat and the contents of the container heated to any desired degree. The container may be 10 provided with a cover if desired. Steam generated by the heating of the water in the space 13 will pass out through the vent 14.

It will be seen that this style of double boiler is very cheaply constructed and while it has a 15 large capacity, takes up relatively small amount of space. I have found the device to be particularly adapted for liquefying honey, in processing green honey, maple sugar and the like.

While I have illustrated the vent as being disposed at the center of the bottom 12 and extending axially through the container, I do not wish 20 to be limited to this as the vent might be otherwise arranged. This boiler could be heated either by an open flame or by introducing live steam 25 into the chamber 13 or by putting a coil in the chamber and passing steam through the coil. In any case, it is the fluid within the chamber 13 that is heated and it is the heat of this fluid 30 which is communicated to the honey or other material in the boiler.

What is claimed is:—

A boiler of the character described, comprising 35 a container having a bottom and a conical false bottom disposed within the container above the first-named bottom and having a vent opening 40 at its center with a vent pipe extending upward from this opening to the top of the container, means bracing the vent pipe from the side wall of the container, an outlet spout extending from 45 the container just above the lowest portion of the false bottom and having a gate, and a filling hopper opening into the space defined between the first-named bottom and the false bottom, the inlet hopper extending up along the side wall 45 of the container and being open at its upper end.

WALTER T. KELLEY.
